(57) **CLAIM**

The ornamental design for a window insulating panel, as shown and described.

DESCRIPTION

FIG. 1: Top right perspective view;

FIG. 2: Bottom left perspective view;

FIG. 3: Top plan view;

FIG. 4: Bottom plan view; and,

FIG. 5: Side edge elevation (all four edges are identical).
The phantom edges are to indicate that the panel is of
indeterminate shape.
